Filed June 16, 1961, Ser. No. 117,638

4 Claims. (Cl. 242—43)

The present invention relates generally to thread or fiber winding mechanisms and more particularly to a builder mechanism adapted to distribute a thread or fiber onto a tube to produce a level thread package thereon.

The mechanism of the present invention is suited for use in winding a wide range of threads or fibers, but the principal application is in the initial winding of glass fiber strands. Accordingly, the invention is presented below in the context of glass fiber manufacture although it should be understood that this is for reason of convenient illustration, and not a limitation on the uses to which the device may be applied.

The production of glass fiber conventionally involves the drawing of several hundred fine molten glass filaments through a bushing or spinneret from a supply of molten glass. The filaments may be cooled, such as by treatment with a water mist, and are then brought together over a grooved carbon gathering wheel. Passage of the filaments over the gathering wheel and further treatment with a size binder forms a single strand of glass fiber or yarn. The strand is then wound onto cylindrical tubes which are driven by a suitable collet assembly.

To permit a full understanding of the advantages provided by the present device, the peculiar problems involved in winding glass fiber should be briefly considered. In the process described above, the filaments and the strand are drawn through the various process stages by the collet assembly driving the tube in rotation. Although this is referred to as a winding operation, the fact must be borne in mind that it is at the same time a drawing operation, and that the condition and uniformity of the drawn fiber is dependent on the maintaining of a constant strand winding speed. Variations in the speed at which the strand is wound will result in variations in strand size due to the molten initial nature of the filaments.

A hydraulic collet drive mechanism such as shown in the inventor's U.S. Patent No. 2,663,541 compensates automatically for the increasing diameter of the fiber package on the tube since a constant driving torque is applied to an increasingly heavier and larger package. However, compensation is made only for the increasing diameter of the entire package and not for the speed changes which are caused by an uneven application of the strand to the winding tube. It is accordingly necessary to distribute the fiber on the tube to form a level package in order to maintain a constant linear strand speed and thus a constant strand size.

A builder has not been developed to produce a fiber package which is completely level along the length of its axial periphery, mainly because of the high speed at which the strand is moving, commonly in excess of 15,000 feet per minute. The tendency of the ends of the package to come unwound and the difficulty of preventing a dwell at the end of the package, among other factors, have produced the situation now existing in which nearly all commercially wound packages are of a humped configuration, the center of the package being of a substantially greater diameter than the ends. Such a package rotating on the collet causes the yarn wound over the center portion of the package to be drawn faster and hence, thinner than that wound at the ends thereof. Because of the non-uniform results produced by the humped

2

package, acceptable commercial packages can presently be wound to only a relatively small diameter which thus limits the weight of the package.

It is therefore, a first object of the present invention to provide a builder mechanism which will distribute a strand or fiber onto a rotating tube to produce a level package thereon, thereby maintaining a substantially constant linear strand speed.

An additional object is to provide a builder mechanism having a snap-action reversing unit which effectively eliminates dwell during the reversing phase of operation.

A further object is to provide a builder mechanism which will effect a lapped strand package such that the package may be easily unwound from its inner or outer surface.

Another object is to provide a builder mechanism which will distribute a thread or fiber onto a rotating tube in a manner which will permit a relatively large thread package to develop thereon, thus increasing the yield on a weight basis per package and reducing the lost time from re-starts to a minimum.

A still further object is to provide a builder mechanism which is characterized by simplicity and durability which is not subject to the usual rapid wear caused by sliding frictional engagement with a fiber.

Still another object is to provide a builder mechanism of the type described which is suited for high speed operation and which is adaptable to speed variation as conditions require.

The present invention in realizing these and other objects includes a lap wheel rotating on an axially reciprocating shaft spaced radially from a collet assembly. The lap wheel is driven in rotation so as to have a surface speed equal to that of the fiber or thread which is to be wound on the collet. The thread is engaged in an angularly disposed groove on the lap wheel which induces a wave into the thread as it passes over the wheel. A snap action reversing mechanism evenly reciprocates the lap wheel drive shaft axially, distributing the thread on the collet in a level manner. The wave induced in the thread by the lap wheel groove prevents sinking of the thread between previously wound turns and allows unwinding of the thread package from either the inside or outside with ease.

Additional objects and advantages of the invention will be more readily apparent from the following detailed discussion of embodiments thereof when taken together with the accompanying drawings in which:

50 FIG. 1 is a plan view showing an embodiment of the present invention installed in the operating position on a dual collet winding unit;

55 FIG. 2 is an end elevation view of the embodiment of FIG. 1 showing the paths taken by the strand during the winding operation;

FIG. 3 is a view taken along line 3—3 of FIG. 2 showing the shaft drive mechanism in side elevation;

FIG. 4 is a view taken along line 4—4 of FIG. 3;

FIG. 5 is a view taken along line 5—5 of FIG. 3;

60 FIG. 6 is a sectional view taken along line 6—6 of FIG. 3 showing the bearing assembly connecting the cylinder shaft with the reciprocating unit;

65 FIG. 7 is a view taken along line 7—7 of FIG. 3 showing the lap wheel assembly support bar and latching mechanism;

FIG. 8 is a view taken along line 8—8 of FIG. 5 showing an end view of the snap action reversing valve mechanism;

70 FIG. 9 is a sectional view taken along line 9—9 of FIG. 8;

FIG. 10 is a view taken along line 10—10 of FIG. 9;

FIG. 11 is a sectional view taken along line 11—11 of FIG. 5 and showing the arrangement of the reversing valve fluid chambers for a first operating position;

FIG. 12 is a view as in FIG. 11 showing the valve fluid chambers arranged for a second operating position;

FIG. 13 is a view as in FIG. 3 of a modified embodiment of the invention utilizing an electric motor to drive a single lap wheel in rotation;

FIG. 14 is a view taken along line 14—14 of FIG. 13;

FIG. 15 is a view taken along line 15—15 of FIG. 13;

FIG. 16 is a view showing a cylindrical fiber package which may be wound using the apparatus of the present invention; and

FIG. 17 is an end elevation view of the embodiment of FIGS. 13—15 mounted on a dual collet winding unit showing the paths of the strand during the winding operation.

Referring to the drawings, FIGS. 1 and 2 show a winding unit 10 which includes dual collet assemblies 12 and 14 which are driven in rotation in the directions indicated. Although conventional commercial collet assemblies could be employed in conjunction with the present device, the collet assemblies illustrated and preferred are the subject of the applicant's U.S. Patent Number 3,099,411.

Secured to the winding unit 10 is the builder drive housing 16. A drive shaft 18 extends from the builder drive housing parallel with the axes of the collet assemblies 12 and 14 supported by a seal tube 20. Rotatably mounted on the end of the drive shaft is a primary lap wheel 22. A secondary lap wheel 24 is mounted on a support bar 26 and is driven by the primary lap wheel.

As shown in the broken line portion of FIG. 1 the drive shaft 18 and the attached lap wheel assembly generally designated 28 are adapted to reciprocate axially, the displacement of the reciprocating stroke corresponding with the axial length of the collet assemblies 12 and 14.

Continuous grooves 30 and 32 on the cylindrical surfaces of the primary and secondary lap wheels are adapted to guide a strand 34 onto one of the collet assemblies. In FIG. 2, the strand 34 is shown passing over the primary lap wheel 22 and onto the collet 12, the lap wheel and of course the winding collet rotating at a surface speed matching the linear strand speed in the directions indicated. Due to the shape and angular disposition of the lap wheel groove, a wave is imparted to the strand as it is wound on the collet which prevents sinking of the wound strand between previously wound strand layers. At the same time, the reciprocating action of the lap wheel assembly, distributing the strand axially along the collet at a uniform rate, and the instantaneous reversing mechanism prevent a build up or dwell of the strand at the ends of the collet and permit the winding of a level package 36 as shown in FIG. 16.

When the desired amount of fiber has been wound on the collet 12, the strand 34 is transferred to the collet 14 as indicated, the strand being guided by the groove 32 in the secondary lap wheel 24. The primary and secondary lap wheels and grooves are identical. The grooves 30 and 32 need not be coordinateably aligned since each functions independently of the other, the strand being engaged by one groove at a time.

The drive mechanism enclosed within the housing 16 which effects a rotation of the lap wheels and reciprocation of the lap wheel assembly is shown in detail in FIGS. 3, 4 and 5. Guide bars 38 secured to the housing floor 40 by guide bar supports 42 provide a supporting means for the reciprocating unit 43.

A crosshead 44 slidably mounted on the guide bars 38 supports a high-speed hydraulic turbine 46. Although any motor having a sufficiently high speed to drive the lap wheels at the strand speed may be satisfactorily employed, embodiment shown utilizes a hydraulic drive such as shown in the inventor's U.S. Patents Nos. 2,663,541,

2,856,749, and 2,857,216. The turbine, as shown, is run in an unenclosed condition, the housing 16 serving to prevent the hydraulic fluid from escaping from the machine. High pressure fluid is led into the turbine through a flexible fluid hose 48 which is connected to a high pressure fluid supply.

A supporting structure consisting of plates 50 and 52 and spacers 54 secures the turbine 46 to the crosshead 44 and serves additionally to support the coupling assembly connecting the hydraulic cylinder to the reciprocating unit, and to support the reversing stop plate, the function and structure of each of which will be discussed below in detail.

A hydraulic cylinder 56 is mounted on the drive housing end wall 58 aligned concentrically with the mounted turbine 46. The manner in which the cylinder shaft 60 is connected with the turbine support structure and also the manner in which the turbine rotor shaft is journaled in this structure is shown in the sectional view of FIG. 6. A coupling body 62 is bolted to the supporting plate 59 as is the back plate 64. The cylinder shaft 60 is threadedly secured to a coupling hub 66 which is held in place by a coupling nut 68. The shoulder 70 of the coupling hub 66 extends into the groove 72 formed between the back plate 64 and the coupling body 62. Flexible inserts 74 on the faces of the groove 72 provide a cushion to absorb the reversing shock of the reciprocating cylinder shaft 60. The turbine 46 drives a motor shaft 76 which extends between the supporting plates 50 and 52. Secured within the rotor shaft 76 is the lap wheel drive spindle 78, the inner end mounting of which is shown in FIG. 6. The spindle 78 terminates in a threaded end 80. A chamber 82 in the coupling body 62 provides clearance for a securing nut 84 on the spindle end 80. Bearings 86 mounted in the supporting plate 50 journal the rotor shaft 76 and spindle 78.

Secured to the end of the turbine 46 and extending therefrom in concentric relation with the spindle 78 is the tubular drive shaft 18, which has an internal diameter sufficiently in excess of the spindle diameter to provide a substantial clearance between the spindle and shaft. The spindle and shaft extend through the housing 16 and through a seal tube 20 attached to the housing which includes a conventional seal ring to seal and support the reciprocating shaft.

The drive shaft 18 extends beyond the seal tube 20 to receive the lap wheel assembly support bar 26 which is secured thereto in the manner indicated in FIG. 7. The support bar, which is secured in a horizontal position, includes a rectangular opening 94, which serves as a supporting guide for the secondary lap wheel axle assembly 96, which is adapted to slide horizontally therein. The position of the axle assembly 96 in the opening 94 is adjusted by means of the spring loaded latch pin 98.

The spindle 78 extends beyond the drive shaft 18 and terminates in a threaded portion 100 as shown in FIG. 4. The primary lap wheel 22 is secured to the threaded spindle end 100. The spindle is journaled within the drive shaft 18 at a point near the lap wheel by suitable conventional bearings (not shown).

The lap wheels 22 and 24, as shown in the partial sectional view of FIG. 4 include a hard rubber insert 102 which forms the peripheral surface of the wheels. Shoulders 104 extending axially from the insert 102 secure the insert against the high centrifugal forces developed by the unusually rapid rotation of the wheels.

The grooves 30 and 32 in the lap wheels are of a modified V shape, having a rounded apex. The groove on each wheel lies in a plane inclined to the axis of the wheel, and thus effects a wave on a strand guided by the groove in rotation.

The insert 102 includes raised annular drive shoulders 106 which extend radially beyond the cylindrical insert surface. With reference to FIGS. 4 and 7 it can be seen that the primary lap wheel drives the secondary lap wheel

due to the frictional contact of their respective drive shoulders 106 which are maintained in engagement by the spring acting on the axle assembly 96 within the opening 94. To disengage the lap wheels, the latch pin 98 is moved outwardly and rotated, causing a pin 108 in the latch pin 98 to be moved out of alignment with a slot 110 in the support bar 26 thus maintaining the lap wheels in a separated condition in spite of the spring force acting on the axle assembly 96. The lap wheels may be reengaged by rotating the latch pin 98 to its original position, permitting the pin 108 to reengage the slot 110.

The reciprocation of the lap wheel assembly, shaft, spindle, and turbine which comprises the reciprocating unit 43 is controlled automatically by the reversing valve 112 which alternates the fluid flow into the cylinder 56. As shown in FIGS. 3 and 5 the reversing valve, which is mounted on the housing 16 by a mounting plate 114, is automatically actuated at the end of each stroke by stops 116 and 118 positioned on stop plate 120 which is bracketed to the supporting plates 50 and 52 of the reciprocating unit. The stops 116 and 118 alternately engage the roller bearing 122 of the pivotally mounted valve trip lever 124 which through an over center spring loaded linkage actuates the valve and provides the desired automatic reciprocating action.

Referring to FIGS. 8, 9 and 10 the snap action linkage which produces the instantaneous reversing action is shown secured to the valve housing 126 by attachment to a boss 128 and interaction with a guide bracket 130 extending therefrom. The trip lever 124 is pivotally mounted on the stud 132 located on the boss 128. A slotted snap arm 134 is coupled to the upper bifurcated end 136 of the trip lever 124 by means of a pin 138 slidably engaging a slot 140 in the snap arm 134. A roller 142 is rotatably mounted in the upper forked end 144 of the arm 134, the roller engaging groove 146 in the guide bracket 130. A spring 148 positioned in compression against a shoulder 150 of the snap arm 134 bears against the bifurcated end of the valve trip lever 124, thus acting to extend the snap arm 134 away from the trip lever 124 and bias the roller 142 against the guide bracket 130 in the groove 146. Hard rubber stops 152 and 154 positioned on the guide bracket 130 and pins 156 and 158 extending from the valve housing serve to limit the movement of the snap arm 134 and the trip lever 124 respectively.

The described valve structure constitutes a snap action over-center mechanism which cannot be stopped on dead center. Movement of the trip lever 124 by the stops 116 and 118 causes the pin 138 to travel in the slot 140 in the snap arm 134 and the snap arm is telescoped within the bifurcated end 136 of the trip lever 124 until the arm and the lever are longitudinally aligned. The snap arm 134 at this point is still in contact with the stop 152 or 154. However, when the trip lever is moved beyond the point of alignment, the spring 148 acting against the end 136 of the lever abruptly swings the snap arm 134 along the groove 146 and into contact with the opposing stop. Movement of the trip lever in the opposite direction will result in the same snap action of the snap arm back to its original position.

To link this snap action motion to the rotary valve stem 160, an arm 162 is rotatably secured to the upper end 144 of the snap arm 134, to which is attached a finger 164 which engages a split collar 166 on the valve stem 160. The valve stem is thus rotated in a manner corresponding with the motion of the snap arm 134.

The fluid flow in the reversing valve is controlled in the manner normally employed in a rotary valve which will be briefly described with reference to FIGS. 11 and 12. The four fluid passages leading into the valve are connected with the fluid pressure pump, the fluid tank, and connections 1 and 2 of the hydraulic cylinder 56 which are respectively labeled P, T, 1 and 2 on the drawings. With the valve actuated by the stop 118 into the

position shown in FIGS. 3 and 8, the interior valve fluid passages would appear as in FIG. 11 in which the high pressure fluid flows through the passage 168 in the valve spool 169 and into the #1 connection in the hydraulic cylinder 56, thus activating the cylinder into motion toward the turbine assembly. The fluid in the opposite end of the cylinder is exhausted through connection #2 and passes through the valve by way of the exhaust passage 170 in the valve spool into the fluid tank.

At the end of the stroke the valve is actuated by the stop 116, and the position of the valve spool 169 is as shown in FIG. 12 in which the high pressure fluid is directed by the passage 172 into the #2 fluid connection of the hydraulic cylinder. At the same time the exhaust passage 170 of the valve spool permits the fluid from the #1 cylinder connection to be exhausted through the valve into the fluid tank. The abrupt snap action of the valve actuating linkage alternates the flow of the high pressure fluid between the #1 and #2 cylinder connections instantaneously so that the reciprocating unit does not dwell at the ends of its strokes.

For operation, the flexible hose 48 is attached to a hydraulic fluid supply and pump to direct high pressure fluid into the turbine. Likewise the inlet P on the reversing valve is connected with a high pressure hydraulic fluid supply, and the port T of the valve is connected with a fluid reservoir. Suitable tubing (not shown) is used to connect the valve ports 1 and 2 with the inlets 1 and 2 of the hydraulic cylinder 56.

The latch pin 98 is actuated to separate the lap wheels and is rotated to maintain the lap wheels in the separated position. The turbine 46 sets the rotor shaft 76 and the drive spindle 78 into rotation upon introduction of high pressure fluid through the flexible hose 48. The speed of rotation of the turbine and lap wheels may be regulated by adjusting the pressure of the hydraulic fluid. Similarly the introduction of a high pressure fluid flow into the inlet P of the reversing valve automatically begins the reciprocating cycle since, as described above, the valve cannot be stopped on dead center and is at all times in a position to actuate the cylinder 56.

The winding operation is started with the collet and primary lap wheel rotating slowly. A strand is first started on the collet in a conventional manner, after which it is manually led into the lap wheel groove. Both the collet and lap wheel are then brought up to the desired winding speed. The reciprocation of the lap wheels distributes the strand axially along the collet surface in an even manner to form a level fiber package. The speed of the reciprocating stroke is governed by the fluid pressure applied to the cylinder 56, and by maintaining the fluid pressure at an unvarying level, the stroke is held at an even speed to produce the desired level thread package. Although a wide variation of reciprocating frequencies may be successfully used, the preferred range for winding glass fibers has been found to be 40 to 60 strokes per minute depending upon the type of glass fibers being wound and the winding speed. The frequency of the reciprocation is controlled by varying the fluid pressure into the reversing valve.

The rotational speed of the lap wheels is adjusted so that the surface speed of the lap wheel is matched to the linear speed of the strand. Since, as pointed out above, it is a purpose of the winder to hold the strand speed constant, the lap wheel rotational speed should need no adjustment after an initial setting for a given winding speed.

The engagement of the strand in the lap wheel grooves imparts a wave to the strand prior to the winding of the strand onto the collet. Because of the fact that the strand is drawn through the builder mechanism by the collet, it can be understood that the amplitude of the wave is substantially decreased at the point at which the strand engages the previously wound strand turns on the package. However, the wave structure remaining is sufficient to preclude the strand from sinking and wedging

between previously wound strands. Instead the wave insures an overlapping of the strand on the previously wound turns such that an even package will result and, equally important, the unwinding of the package may proceed easily from the inside or outside.

The abrasive frictional action usually encountered in distributing glass fibers at high speeds is obviated by the present lap wheels, which moving at the same speed as the strand, eliminate damaging frictional contact.

For transfer of the strand to the second collet 14, the latch pin 93, following the starting of the strand on the second collet and the introduction thereof in the secondary lap wheel groove, is manipulated to engage the secondary and primary lap wheel shoulders. The primary then drives the secondary lap wheel and the winding operation is carried out as previously described.

A modified embodiment of the invention is shown in FIGS. 13-15 and 17 which utilizes a high speed electric motor to drive the lap wheel. A main advantage of such an electric drive is that a single lap wheel may be used to distribute fibers onto dual collet assemblies since the electrically driven wheel may be reversed to permit its use with either of two collets. An additional and obvious advantage over the turbine driven embodiment is the absence of hydraulic fluid lines and the need for an additional high pressure fluid supply.

Referring to FIGS. 13-15, the modified embodiment is shown enclosed in a housing 174 which is mounted on a winding unit 10. A reciprocating unit frame 176 is slidably disposed within the housing on guide bars 178. A high speed electric motor 180 is secured within the frame 176 and drives a grooved sheave 182. A smaller grooved sheave 184 is engaged with and driven by the sheave 182 and is mounted on a drive spindle 186 supported within a tubular drive shaft 188 which is anchored to the frame 176. The drive shaft 188 is journaled in a bearing tube 190 secured to the exterior face of the housing 174. A single lap wheel 192 is secured to the spindle 186 and is of a design and construction similar to the lap wheels of the preferred embodiment.

The reciprocating unit frame 176 is driven as in the preferred embodiment by a hydraulic cylinder 194 which is controlled by an automatic snap action hydraulic rotary valve 196 actuated by a stop plate 198 mounted on the frame 176.

Power is supplied to the motor through rails 200 secured in an insulated manner to the housing 174 parallel with the reciprocating path of the motor. Brushes 202 mounted on the motor frictionally engage the rails and conduct current to the motor field and armature.

Operation of the modified embodiment is similar in most respects to that of the preferred embodiment. The paths followed by a strand during winding on each of the two collets of the winder 10 is shown in FIG. 17. The single lap wheel 192 is rapidly reversed during transfer of the strand to the second collet. The lap wheel speed during the builder operation is controlled by varying the armature voltage in the motor which may be done by use of a conventional control system.

Actual operation of the present invention under normal winding conditions using the conventional sized winding tube and collet has proven the present builder mechanism effective to provide a level wound package. Accordingly, the diameter of the package can be greatly increased over conventionally wound packages since the winding speed is as a result maintained substantially constant. It has, for instance, been found with the present device that a strand may be wound on a collet for a period of approximately one hour as contrasted to ten or fifteen minutes with conventional equipment at the same winding speed. The larger package size now possible substantially decreases the frequency of the strand transfer operations and increases the efficiency of the winding machine, in addition to providing a more economically transportable and efficiently processable package.

Manifestly minor changes in details of construction can be effected by those skilled in the art without departing from the spirit and the scope of the invention as defined in, and limited solely by the appended claims.

5 I claim:

1. A builder mechanism for distributing a thread or fiber onto a rotating tube comprising a housing, a reciprocating unit slidably secured to said housing, means for reciprocating said reciprocating unit comprising a hydraulic cylinder secured to said housing operatively engaging said reciprocating unit, a reversing valve secured to said housing having a rotatable valve control, means comprising a hydraulic circuit operatively connecting said valve and cylinder with a fluid supply such that fluid flow actuating said cylinder is controlled by said valve, valve reversing means comprising a spring-loaded over-center linkage on said valve coupled to said rotatable valve control, said over-center linkage comprising a trip lever pivotally secured to a pivot stud on said valve, and a snap arm pivotally connected to said trip lever spring-biased between said trip lever and a guide bracket on said valve, an arm and finger operatively connecting said snap arm and said rotatable valve element, the thrust of said over-center linkage being borne by said pivot stud and guide bracket and thus prevented from affecting rotation of said rotatable valve control, and means on said reciprocating unit for tripping said trip lever upon completion of each stroke of reciprocation thereby actuating said valve control and instantaneously reversing said hydraulic cylinder; said reciprocating unit comprising a motor, a spindle parallel with the path of reciprocation driven in rotation by said motor, and a grooved lap wheel on said spindle, whereby said builder mechanism may be positioned adjacent a rotating tube so as to engage a thread or fiber in said grooved lap wheel prior to the winding thereof on the tube while rotating said lap wheel at a speed corresponding with the linear winding speed of the thread, and reciprocating said reciprocating unit at a constant rate to spread the thread along 40 said tube, thus providing an evenly distributed thread package on said tube.
2. A self-starting hydraulic reciprocating engine for actuating a reciprocating member comprising a housing, a hydraulic cylinder secured to said housing operatively engaging the reciprocating member, a hydraulic reversing valve secured to said housing having a rotatable valve control, means comprising a hydraulic circuit operatively connecting said valve and cylinder with a fluid supply such that fluid flow actuating said cylinder is controlled by said valve, valve reversing means comprising a spring-loaded over-center linkage on said valve coupled to said rotatable valve control, said over-center linkage comprising a trip lever pivotally secured to a pivot stud on said valve, and a snap arm pivotally connected to said trip lever spring-biased between said trip lever and a guide bracket on said valve, an arm and finger operatively connecting said snap arm and said rotatable valve element, the thrust of said over-center linkage being borne by said pivot stud and guide bracket and thus prevented from affecting rotation of said rotatable valve control, and means on the reciprocating member for tripping said trip lever upon completion of each stroke of reciprocation thereby actuating said valve control and reversing said hydraulic cylinder.
3. A builder mechanism for traversing a thread or fiber along a rotating tube to provide a level wound thread or fiber package comprising a housing, a reciprocating unit slidably secured to said housing, means on said reciprocating unit engaging and guiding a thread or fiber 55 proximate the rotating tube to traverse said thread or fiber along the tube, a hydraulic snap-action reversing valve secured to said housing having a rotatable valve control, means comprising a hydraulic circuit operatively connecting said valve and cylinder with a fluid supply such that fluid flow actuating said cylinder is controlled

by said valve, said valve actuated by an over-center linkage comprising a pivot stud on said valve parallel with said rotatable valve control, a valve trip lever pivotally mounted on said pivot stud, a snap arm pivotally connected with said trip lever, means permitting movement of the snap arm and trip lever pivotal connection longitudinally along said snap arm, a guide bracket on said valve, bearing means on said snap arm operatively engaging said guide bracket, spring means on said snap arm biasing said snap arm away from said trip lever and against said guide bracket, an arm and finger extending from said snap arm connecting said snap arm with said rotatable valve control, stop means limiting rotation of said trip lever, said pivot stud, guide bracket, and stop means absorbing the thrust of said spring means and preventing the thrust from affecting the rotation of said valve control, and means on said reciprocating unit for tripping said trip lever upon completion of each stroke of reciprocation thereby actuating said valve control and instantaneously reversing said hydraulic cylinder.

4. A self-starting hydraulic reciprocating engine for actuating a reciprocating member comprising a housing, a hydraulic cylinder secured to said housing operatively engaging the reciprocating member, a hydraulic reversing valve secured to said housing having a rotatable valve control, means comprising a hydraulic circuit operatively connecting said valve and cylinder with a fluid supply such that fluid flow actuating said cylinder is controlled by said valve, valve reversing means comprising a spring-loaded over-center linkage on said valve, said over-center linkage comprising a pivot stud on said valve parallel with said rotatable valve control, a valve trip lever piv-

otally mounted on said pivot stud, a snap arm pivotally connected with said trip lever, means permitting movement of the snap arm and trip lever pivotal connection longitudinally along said snap arm, a guide bracket on said valve, bearing means on said snap arm operatively engaging said guide bracket in slidable relation therewith, spring means on said snap arm biasing said snap arm away from said trip lever and against said guide bracket, an arm and finger extending from said snap arm connecting said snap arm with said rotatable valve control, stop means limiting rotation of said trip lever, said pivot stud, guide bracket, and stop means absorbing the thrust of said spring means and preventing the thrust from affecting the rotation of said valve control, and means on the reciprocating member for tripping said trip lever upon completion of each stroke of reciprocation thereby actuating said valve control and reversing said hydraulic cylinder.
